UNITED STATES PATENT OFFICE.

ALFRED AULETTA, OF BAYONNE, NEW JERSEY, ASSIGNOR OF ONE-THIRD TO PETER PARIS, OF BAYONNE, NEW JERSEY.

SHUTTLE-OPERATING MECHANISM.

Application filed May 27, 1922. Serial No. 564,089.

To all whom it may concern:

Be it known that I, ALFRED AULETTA, a subject of the King of Italy, and resident of Bayonne, in the county of Hudson and State 5 of New Jersey, have invented certain new and useful Improvements in a Shuttle-Operating Mechanism, of which the following is a specification.

This invention relates to a shuttle operating mechanism.

Its object is the production of such a mechanism that is very simple in construction and with but few parts. A second object of the invention is to swing the picker sticks thereof through the intervention of gears, that are partially turned with the swinging of the lay batten of the loom for which the picker sticks are provided. A third object is to provide adjustable means 20 to turn said gears, so that their operations can be timed one with the other. Other objects will appear in the specification and claims.

In the accompanying drawings Fig. 1 represents a front elevation of a loom with the improved shuttle operating mechanism incorporated therewith; Fig. 2 shows a top plan view of Fig. 1; Fig. 3 indicates an enlarged left hand side view of Fig. 1; Fig. 30 4 shows an enlarged fragmentary portion of Fig. 1; Fig. 5 is a top view of Fig. 4; Fig. 6 shows a section of Fig. 4 on the line 6, 6; Fig. 7 indicates a section of Fig. 3 on the line 7, 7; Fig. 8 represents an elevation of 35 some details; Fig. 9 shows a right hand side view of Fig. 8 and Fig. 10 is a top view of Fig. 8.

The loom is indicated with the similar side frames A, A', which comprise each the 40 upper horizontal member 20, the lower horizontal member 21, the front vertical member 22, the rear vertical member 23 and the central vertical member 24.

Longitudinal members 25, 26 and 27 connect the frames A and A'. A breast beam 30 also connects the frames A and A'. Journal brackets 32 are formed with the members 21 and support the rock shaft 33. A pair of similar U shaped arms are indicated in their entireties by the letters B and

B'. A sleeve 35 is formed at the bottom end of each arm and is fastened to the shaft 33. An angular shaped seat 36 is formed at the top end thereof. A pair of journal ears 37 is formed at the top end of each of 55 the arms B, B'. A lug 38 is formed with each of the said arms. A lay batten C with the guide openings 43 is seated upon and fastened to the seats 36 of the arms B, B'. Journal brackets 44 are supported upon the 60 members 20 of the frames A, A' and have journaled therein the usual crank shaft 45 having the wrist pins 46. Links 47 connect the wrist pins 46 and the pins 48 that are fastened to the journal ears 37. A U-shaped 65 frame 50 extends from the member 20 of the frame A. A journal bearing 51 is supported on the frame 50 and in turn supports one end of the crank shaft 45. A clutch pulley 52 is fastened to the said crank shaft 70 and a hand wheel 53 is also fastened thereto.

The lay batten C has connected thereto the usual similar shuttle boxes D, D' for the shuttle 54. Each shuttle box comprises the rear wall 55 with its lower longitudinal 75 portion fastened to the said lay batten C. The wall 55 has an opening 56 in which is pivoted the arm 57, by means of the pivot 58. An angular guide plate 60 is fastened to the lay batten C for the shuttle box. 80

A bracket plate 62 has one end thereof fastened to each of the arms B, B' and their lugs 38. A bracket 63 having the journal bearings 64 and 65 is fastened to the plate 62, and a journal bracket 66 is also fastened to said plate. A spindle 67 is journaled in the bearing 64 and has fastened thereon the bevel pinion 68. A squared end 69 with the threaded shank 70 is formed with the spindle 67. A shaft 73 is journaled in the bearings 65 and 66 and has fastened thereto the bevel gear 75, which in this instance is double the diameter of the bevel pinion 68 and meshes therewith. A sleeve 76 with the contact arm 77 is adjustably 95 fastened to the upper end of the shaft 73. Pinions 78 are fastened to the crank shaft 45. Journal brackets 79 are supported on each of the members 20 of the frames A, A'. A pivot 80 extends from each of the brack- 100

ets 79 and has journaled thereon a spur gear 81 which in this instance is double the diameter of the pinion 78, with which it meshes. A cam groove 82 is formed in each 5 of the spur gears 81. A bracket E is adjustably fastened to the inner faces of each of the members 20 of the frames A and A'. Each of the brackets E comprises the body portion 83 with the elongated openings 84 and the upper portion 85. Bolts 86 extend from the members 20 and extend through the openings 84. By means of the bolts 86 the brackets E are adjustably bolted to said members 20. In the portion 85 is journaled 10 a pivot 88, that has formed therewith a sleeve support 89 provided with the set screw 90 and the threaded shank 92. A guide bracket 93 is fastened to the vertical member 24 of each of the frames A and A'. A lever 95 is adjustably supported in the sleeve support 89 and clamped in position by means of the set screw 90. A roller 96 is pivoted to one end of each of the levers 95 and engages the cam groove 82 of the spur 15 gear 81. The cam groove 82 of the gear 81 of the frame A is vertically reversed from the cam groove of the gear 81 of the frame A'. A link 100 has one end pinned to the lever 95 and its other end pinned to the stop 20 plug 101. The latter is guided in the guide bracket 93 and can be lowered into and raised out of the path of the contact arm 77. A picker stick 104 is pivoted adjacent to its lower end to the bracket plate 62, by 25 means of the pin 105. The upper end of the picker stick is surrounded by the usual picker 106, which is guided in the shuttle box in the usual way. An arm 108 bears on the bracket plate 62 and has a square opening which engages the squared end 69 of the spindle 67. A washer 109 around the shank 70 bears on the arm 108. A nut 110 on the shank 70 maintains the arm 108 in proper position. A link 112 has one end 30 pinned to the picker stick 104 and its other end is pinned to the arm 108. A spring 115 has one end fastened to the bottom end of the picker stick 104 and the other end is fastened to the bracket plate 62. 35 An operating handle 120 has formed therewith a sleeve 121 which is pivoted to the member 22 of the frame A. A lug 122 extends from the handle 120. A safety device comprises the usual member with the legs 125 and 126. A latch projection 127 extends from the leg 126. A supporting bracket 128 is fastened to the member 22 and slidably supports the leg 126, and the leg 125 is supported on the member 20 of the frame A. A rod 130 is journaled to the 40 lower face of the lay batten C and on each end thereof is fastened an angle shaped arm with the legs 131 and 132. A pair of arms 133 are fastened to the rod 130 and are disposed to swing in the path of the latch 45

projections 127. A lever 135 is pivoted to the frame 50 and one end thereof is pivoted to the clutch mechanism 136 of the clutch pulley 52. A link 137 connects the lever 135 and the handle 120. 70

To operate the shuttle operating mechanism, the loom is first started in operation by means of the operating mechanism, the loom is first started in operation by means of the operating handle 120, which fastens 75 the clutch pulley 52 to the crank shaft 45 and with the revolutions of the clutch pulley the shaft 45 is turned. Through the intervention of the pitmans 47 the lay batten C is swung forwardly and backwardly. The 80 bracket plates 62 with their appurtenances swing with batten C and when either contact arm 77 strikes its stop plug 101, the adjacent shaft 73 is turned through a small angle which turns the bevel gear 75 through 85 a corresponding angle. The bevel pinions 68 being in mesh with the bevel gears 75 and being one-half the pitch diameter thereof turn through an angle twice as large and swing the picker sticks 104 alternately to 90 their vertical positions, which will cause the pickers 106 to impinge against the shuttle 54 and alternately drive it from one shuttle box to the other.

When the arms B, B' have been swung to 95 the ends of their strokes distant from the breast beam 30 the springs 115 force the picker sticks to their outward positions as best shown in Fig. 1.

The brackets E are clamped to the members 20 of the frames A and A', to produce the required strokes for the stop plugs 101, in relation to the contact arms 77, to enable said arms 77 to swing clear of said plugs at the proper times, that is to say, when one of the arms 77 strikes its stop plug 101, the other arm 77 must swing clear of its contact plug 101. By this disposition of parts the picker sticks 104 at the end of the lay batten swing to drive the shuttle 54 alternately 110 from one shuttle box to the other.

Various modifications may be made in the construction of the shuttle operating mechanism and the present exemplification is to be taken as illustrative and not limitative of the invention. 115

Having described my invention what I desire to secure by Letters Patent and claim is:

1. In a shuttle operating mechanism the 120 combination of a rock shaft, arms with the lower ends fastened to the rock shaft, a lay batten secured to the upper ends of said arms, a shuttle box at each end of the lay batten, a bracket plate fastened to each of said arms, a picker stick pivoted to each bracket plate, a bevel pinion and bevel gear meshing with each other and journaled to the bracket plate, connections between each picker stick and said bevel pinion and means 125

to alternately partially turn each bevel pinion and thereby swing its accompanying picker stick.

2. In a shuttle operating mechanism the

5 combination of a bracket plate, means to swing the plate, a picker stick pivoted to the plate, a shaft journaled to the plate, a gear fastened to the shaft, a contact arm extending from the shaft, a stop plug, means 10 to locate the stop plug in the path of the contact arm.

3. In a shuttle operating mechanism for a loom the combination of a shaft swinging with the lay batten of the loom, a bevel gear 15 fastened to one end of the shaft, a contact arm extending from the shaft, a bevel pinion meshing with the bevel gear, a picker stick oscillated by its coaction with the bevel pinion and a movable stop plug in the path 20 of the contact arm.

4. In a shuttle operating mechanism for a loom the combination of a rock shaft, a pair of arms with their lower ends fastened to the shaft, a lay batten secured to the up- 25 per ends of the arms, a crank shaft journaled in the loom, pitmans connecting the crank shaft and the upper end of said arms,

a bracket plate fastened to each arm, a bracket with a pair of journal bearings fastened to the bracket plate, a journal bracket fastened to the bracket plate, a spindle journaled in one of said journal bearings and in 30 said journal bracket, a bevel gear fastened to the spindle, a second spindle journaled in

35 the other journal bearing and extending through the bracket plate, a bevel pinion fastened to the second spindle and meshing with said bevel gear, an arm bearing on the bracket plate and fastened to the second 40 spindle, a picker stick pivoted to the bracket plate, a link connecting said arm and the picker stick, a sleeve with a contact arm adjustably fastened to the first spindle, a guide bracket in the loom adjacent to the contact 45 arm, a stop plug slidably located in said guide bracket and means to locate the stop plug in the path of the contact arm.

5. In a shuttle operating mechanism for a loom the combination of a rock shaft, arms 50 with the lower ends fastened to the rock shaft, a lay batten fastened to the arms, a shuttle for a shuttle box at each end of the lay batten, a bracket plate fastened to each of said arms, a picker stick pivoted to each 55 bracket plate, a bevel pinion and a bevel gear meshing with each other journaled to the bracket plate, a spindle supporting the bevel pinion, a shaft supporting the bevel gear, connections between each picker stick

60 and the spindle of its accompanying bevel pinion, a crank shaft journaled in the loom, connections between the crank shaft and said arms, a guide bracket adjacent to each shaft of the bevel gears, a stop plug guided in 65 each guide bracket, means to move each stop

plug and a sleeve with a contact arm fastened to each shaft of the bevel gears and located to contact with the stop plugs.

6. In a shuttle operating mechanism for a loom the combination of a pair of side 70 frames, longitudinal members connecting the side frames, a crank shaft journaled in the loom, a rock shaft journaled to the side frames, arms with their lower ends fastened to the rock shaft, pitmans connecting the

75 crank shaft and said arms, a lay batten fastened to the arms, shuttle boxes for a shuttle carried on the lay batten, a bracket plate fastened to each arm, a bracket with a pair of journal bearings fastened to each bracket

80 plate, a journal bracket fastened to the bracket plate with its bearing in alignment with one of the pair of said journal bearings, a shaft journaled in the journal bracket

85 and the coaxial journal bearing of said bracket, a bevel gear fastened to the shaft, a spindle journaled in the other journal bearing, a bevel pinion fastened to the pinion and meshing with the bevel gear, a picker

90 stick pivoted to each bracket plate, an arm with one end fastened to the spindle, a link connecting the arm and its adjacent picker stick, a journal bracket supported on each side frame, a pivot extending from each of

95 the latter brackets, a spur gear with a cam groove supported on each of said pivots, a pair of pinions fastened to the crank shaft meshing with said spur gears, a bracket adjustably connected to each frame, a lever

100 adjustably pivoted to each of the latter brackets, a roller at one end of the lever engaging the cam groove of its accompanying spur gear, a link pivoted to the other end of each lever, a guide bracket fastened to each frame, a stop plug with one end thereof pivoted to each lever and guided in the guide bracket and a sleeve with a contact arm fastened to each shaft of the bevel

105 gears located in the path of the stop plugs.

7. In a shuttle operating mechanism for a loom the combination of a pair of swinging arms, a lay batten supported on the arm, a shaft swinging with each arm, a picker stick swinging with each arm, gears inter-

110 posed between each picker stick and said shaft, a sleeve with a contact arm fastened to each shaft, a guide bracket adjacent to each of said shafts, a stop plug slidably supported in each guide bracket and means to move

115 the stop plug in the path of its adjacent contact plug.

8. In a shuttle operating mechanism for a loom the combination of a pair of swinging arms, a lay batten swinging with the arms, a shaft adapted to oscillate with each

120 swinging arm, a pivoted picker stick for each arm, connections between each picker stick and its accompanying shaft, a sleeve with a contact arm for each shaft, a pair

125 of guide brackets in the loom, one of said

130

brackets adjacent to each of said shafts, a stop plug slidably supported in each guide bracket, a link with one end pinned to each stop plug, a pair of brackets adjustably fastened to the loom, a lever pivoted in each of the latter brackets, one end of each lever pinned to one of said links, a pair of rotat-

ing spur gears each with a cam groove in the loom, and a roller pivoted to each of said levers engaging one of said cam grooves. ¹⁰

Signed at Bayonne in the county of Hudson and State of New Jersey this 9th day of May A. D. 1922.

ALFRED AULETTA.
